US0D1060692S

(12) **United States Design Patent** (10) **Patent No.:** **US D1,060,692 S**
(45) **Date of Patent:** **** Feb. 4, 2025**

(54) **PHYSIOTHERAPY APPARATUS**

(71) Applicant: **Hunan RAYJU Technology Co., LTD**,
Changsha (CN)

(72) Inventors: **Mingyu Tang**, Changsha (CN); **Zhijun Chen**, Changsha (CN); **Xiaochun Li**, Changsha (CN)

(73) Assignee: **Hunan RAYJU Technology Co., LTD**,
Changsha (CN)

(**) Term: **15 Years**

(21) Appl. No.: **35/519,864**

(22) Filed: **Jan. 9, 2024**

(80) **Hague Agreement Data**

Int. Filing Date: **Jan. 9, 2024**

Int. Reg. No.: **DM/234731**

Int. Reg. Date: **Jan. 9, 2024**

Int. Reg. Pub. Date: **Feb. 2, 2024**

(51) **LOC (15) Cl.** **24-01**

(52) **U.S. Cl.**

USPC **D24/200; D24/188**

(58) **Field of Classification Search**

(57)

CLAIM

The ornamental design for physiotherapy apparatus as shown and described.

DESCRIPTION

1.1 Perspective view

1.2 Front view

1.3 Back view

1.4 Left view

1.5 Right view

1.6 Top view

1.7 Bottom view

1.8 Perspective view

1.9 Perspective, shown in a first condition of use with multiple apparatus

1.10 Perspective, shown in a second condition of use

The equal-length broken lines in the drawings depict environmental structure and form no part of the claimed design.

1 Claim, 10 Drawing Sheets
